*Primary Examiner—Ruth McInroy**Attorney, Agent, or Firm—George A. Bode***[57] CLAIM**

The ornamental design for a face protector having pivoting shield, as shown and described.

DESCRIPTION

FIG. 1 is a top plan view of a face protector having pivoting shield showing my new design;

FIG. 2 is a right side elevational view thereof;

FIG. 3 is a front elevational view thereof;

FIG. 4 is a bottom plan view thereof;

FIG. 5 is a left side elevational view thereof;

FIG. 6 is a rear elevational view thereof;

FIG. 7 is a top frontal perspective view thereof; and,

FIG. 8 is an exploded top frontal perspective view thereof.

The head shown in broken lines in FIGS 2 and 5 is shown for illustrative purposes only and forms no part of the claimed design.

FIG. 1
